[57] CLAIM

The ornamental design for a female connector, as shown and described.

DESCRIPTION

FIG. 1 is a front view of the new design of a female connector;

FIG. 2 is a rear view of the female connector of FIG. 1;
FIG. 3 is a top view of the female connector of FIG. 1;
FIG. 4 is a bottom view of the female connector of FIG. 1;
FIG. 5 is a right side view of the female connector of FIG. 1 (the left side view being a mirror image thereof); and,
FIG. 6 is a perspective view from the front side of the female connector, shown in relation to a male connector component
(in phantom line) which is not a part of the design claimed
herein.
